(57) **CLAIM**

The ornamental design for a chair as shown and described.

DESCRIPTION

FIG. 1 is a top front right perspective view of a chair showing our new design;

FIG. 2 is a bottom back left perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of part 9 in FIG. 2.

The dotted broken lines in the drawings are for the purpose of illustrating portions of the chair that form no part of the claimed design. The dash-dot broken lines in FIG. 9 are for the purpose of illustrating the boundaries of the enlarged fragment shown in FIG. 9, and form no part of the claimed design.
